UNITED STATES PATENT OFFICE.

HUBERT R. ALLEN, OF NEW HAVEN, CONNECTICUT, ASSIGNOR TO THE
WINCHESTER REPEATING ARMS COMPANY, OF SAME PLACE.

MACHINE FOR GREASING BULLETS.

SPECIFICATION forming part of Letters Patent No. 240,635, dated April 26, 1881.

Application filed February 19, 1881. (No model.)

To all whom it may concern:

Be it known that I, HUBERT R. ALLEN, of New Haven, in the county of New Haven and State of Connecticut, have invented new Improvements in Machines for Greasing Bullets; and I do hereby declare the following, when taken in connection with the accompanying drawings and the letters of reference marked thereon, to be a full, clear, and exact description of the same, and which said drawings constitute part of this specification, and represent, in—

Figure 1, a top or plan view; Fig. 2, a transverse section through the reservoir; Fig. 3, a side view of the wick-tubes.

This invention relates to an improvement in machines for placing the lubricating material on bullets, commonly called "bullet-greasing," the object being to apply the lubricating material to the bullet while it is being rotated, and so that several coatings may be applied, if desired; and the invention consists in a revolving disk and a stationary segment, arranged to leave a space between the periphery of the disk and the segment, whereby bullets or cartridges with bullets introduced into said space will be caused to roll through said space by the rotation of the disk, and in such rotation come into contact with and receive a coating of the lubricating material, as more fully hereinafter described.

A is the disk, and B the segment, arranged to leave a space, *a*, between them, the said disk caused to revolve and impart rotation to the bullets or cartridges placed between them, substantially as do the disk and segment in the well-known bullet-grooving machines.

A floor, C, below the space *a* serves to support the bullet or cartridge in a vertical position, the same as in the bullet-grooving machine, but preferably revolves with the disk A at the same or a slower rate of revolution.

D is the reservoir for the grease or lubricating material, the material being held therein in a melted condition by heat directly applied, or otherwise. From the reservoir at one or more points an outlet, *d*, is arranged, preferably provided with a stop-cock, *e*, or other gate. The outlet *d* leads to a tube, *f*, standing in a horizontal plane, its outer end near where

the lubricating material is to be applied. Within this tube is a wick or other suitable conductor, *h*, (see Fig. 2,) through which the lubricating material will freely pass. The wick *h* projects slightly from the tube, and so that the passing bullet will roll in contact with the protruding end of the wick.

For convenience of adjusting the wick an adjuster, *i*, is arranged upon the wick, the shaft of which extends outside the tube, and is provided with a head, *n*, for turning it, substantially like wick-adjusters in lamp-burners. Preferably several of these wick-tubes are arranged at the space between the disk and segment, as seen in Fig. 1, at a short distance from each other, so that as the bullet passes the first it will receive a certain amount of the warm grease, and which, before it reaches the second, will have cooled, so that the second wick will apply an additional coating, and so on—or one, for instance, may have a thin wick, as in Fig. 3, which will apply the grease directly into the groove of the bullet, while another may be broader, as in Fig. 2, and apply the grease over a greater extent. Usually this greasing is to be performed after the bullet has been introduced into the shell, and as the last operation in completing the cartridge. The cartridges are set head downward upon the floor C and carried along by it into the space *a*.

In order to separate the cartridges from each other to such an extent that one will not rub the next, I apply a separator, E, near the entrance to the recess *a*, which consists of a toothed wheel arranged so that as the cartridge on the disk advances it will strike between two teeth, as indicated at *r*, Fig. 1, and then advancing will turn the separator, so that the next cartridge will come into the next space. This leaves a distance between successive cartridges equal to the thickness of each tooth. This separator will be unnecessary when the floor is made to revolve in the same direction as the disk, but at a slower rate of speed, as in the patent of Borchardt, dated July 21, 1874, No. 153,810.

Other means than the tubes and wicks may be employed for bringing the lubricating material to the required point; but the wick is

believed to be the best arrangement for so doing.

I claim—

1. The combination of a revolving disk and corresponding segment, arranged to leave a space between, and provided with a floor upon which the cartridge or bullet is supported, with one or more greasers arranged in relation to the disk and segment, substantially as described, so that a bullet, in passing through said space, will roll in contact with said greaser or greasers, substantially as described.

2. The combination of a revolving disk and corresponding segment, arranged to leave a space between them, through which cartridges or bullets introduced in said space will be caused to roll, with a wick arranged in a tube which receives a supply of lubricating material, the outer end of said wick in such relation to the space between the disk and segment that the cartridge or bullet rolled through

said space will roll in contact with the outer end of said wick, substantially as described.

3. The combination of a revolving disk and corresponding segment, arranged to leave a space between, and provided with a floor upon which the cartridge or bullet is supported, with one or more greasers arranged in relation to the disk and segment, substantially as described, so that a bullet, in passing through said space, will roll in contact with said greaser or greasers, and with a separator, substantially such as described, to arrange the cartridges or bullets so that they enter and roll through the space between the disk and segment without contact with each other, substantially as described.

HUBERT R. ALLEN.
